UNITED STATES PATENT OFFICE.

WALTER H. KNIGHT, OF NEW YORK, N. Y.

ELECTRIC RAILWAY.

SPECIFICATION forming part of Letters Patent No. 425,950, dated April 15, 1890.

Original application filed March 13, 1886, Serial No. 195,133. Divided and this application filed September 21, 1887. Serial No. 250,342. (No model.)

To all whom it may concern:

Be it known that I, WALTER H. KNIGHT, a citizen of the United States, residing at New York, in the county of New York, State of New York, have invented certain new and useful Improvements in Electric Railways, of which the following is a specification.

This application is a division of application Serial No. 195,133, filed March 13, 1886, and also showing certain subject-matter which is claimed in Patent No. 406,743, granted to me July 9, 1889, which patent is also a division of the said original application.

My invention consists in certain features of construction of a contact device adapted to maintain a traveling electrical connection between the supply-conductor of an electric railway and the propelling-motor, and particularly in the means for connecting the contact device with the vehicle, all of which are described hereinafter and claimed.

In the accompanying drawings, illustrating my invention, Figure 1 shows side and end views of the contact device in engagement with the supply-conductors inclosed in a slotted conduit, and Figs. 2, 3, 4, 5, and 6 illustrate in detail various specific features of the contact device and the means for connecting the flexible conductor therewith.

In the views, A is the frame of a "car" or "locomotive," by which terms I intend to cover any electrically-propelled vehicle, and B is a contact device or plow, consisting of two insulated conducting-cores *w w*, embedded in insulating-panels, which are supported between the legs S S of a protecting metallic frame. Each core has a foot K attached to it by a spring-hinge, and a contact-shoe L, adapted to press against the conductor, is carried by each foot. These shoes normally

contact with the supply-conductors F F', which in Fig. 1 are shown inclosed in a slotted conduit. The plow is supported by a tubular traveler c, adapted to slide freely in a transverse guide C upon the vehicle, and each of its three legs is provided with a wearing-plate b where it passes through the slot of the conduit. All these features, however, relating to the general construction of the plow, as well as the supplemental manual contact device E, with its contacts *e e'*, (illustrated in

Fig. 1,) have been already claimed in my patent, No. 406,743, and are shown herein only as incidental to the present invention, which I now proceed to describe.

Extending up through the metallic frame of the plow on each side of the traveler c is a pin *w'*, which is insulated from the frame by an intermediate wooden bushing M, and passes down into contact with the insulated core *w* at its lower end, while at its outer end it terminates in a ball or knob X. To the rigid shank of the contact-plow at the point M outside of the conduit there is jointed a flexible conductor O, which forms the electrical connection between the contact device and one of the terminals *a a'* of the propelling-motor. This point is shown in an enlarged scale in Figs. 3 and 4, wherein the flexible conductor, consisting of the stranded core P and an insulating-covering, is connected to a metallic tube T, which at its lower end is enlarged to a spherical shape with radial splits, so that it will expand and grasp the ball X upon the conducting-pin.

U is a wooden sheath inclosing the split metallic tube. The engagement of the tube T with the conducting-pin forms what may be generically termed a "spring-clip connection," which allows the flexible conductor between the contact device and motor to be automatically detached when the plow is moved too far to one side or is otherwise displaced. It also constitutes a universal joint, permitting movement of the contact-plow in any direction without strain on the conductor.

I am aware that many different forms of joints and connections may be employed which will fulfill the same functions as those specifically described herein.

What I claim, and desire to secure by Letters Patent, is—

1. In an electric railway, the combination of a contact device movable relatively to the car and a flexible connection between it and the car attached to the contact device by a spring-clip, as described.

2. In an electric railway, the combination of a contact device movable relatively to the car and a flexible conductor between it and the car provided with an electrical spring-clip connection.

3. In an electric railway, the combination of a supply-conductor inclosed in a conduit, a contact device extending into the conduit and connected with a vehicle on the roadway, 5 but movable laterally relatively thereto, and an electrical conductor leading from the said contact device to the motor on the vehicle having an electrical spring-clip connection.
4. The combination, in an electric railway, 10 of a contact-plow comprising an insulated conductor and a protecting-frame, with a conducting-pin extending out from the frame, a flexible conductor in circuit with the propelling-motor, and a spring-clip connection between the motor and pin, as set forth.
5. In an electric railway, the combination of an electrically-propelled vehicle with a contact device movable relatively to the vehicle and mechanically connected thereto, and a 15 flexible conductor forming the electrical connection between the contact device and the propelling-motor and provided with an automatically-detachable connection, as described.
6. The combination, with an electrically-propelled vehicle, of a supply-conductor inclosed in a conduit, a traveling contact thereon, and a flexible jointed conductor between said contact and the vehicle, the joint being at a point 20 outside of the conduit.
7. The combination of an electrically-propelled vehicle, a supply-conductor inclosed in a slotted conduit, and a traveling contact de- 25
- vice extending through the slot, with a conductor jointed at one end to the contact device at a point outside of the conduit and forming the electrical connection with the propelling-motor. 30
8. The combination, with an electrically-propelled vehicle, of a supply-conductor inclosed in a slotted conduit and a contact device having a rigid shank extending through the slot, with a conductor in circuit with the propelling motor and jointed to the upper end of the said contact device, as described. 35
9. The combination, with an electrically-propelled vehicle, of a supply-conductor inclosed in a slotted conduit, a traveling contact thereon mechanically connected with the vehicle, and an independent jointed conductor forming an electrical connection between the contact device and the propelling-motor. 40
10. The combination, with an electrically-propelled vehicle and a supply-conductor inclosed in a slotted conduit, of a contact device extending through the slot and a conductor having at one end a universal joint attachable to the said contact device and forming the electrical connection with the propelling-motor. 45
